CLAIM

The ornamental design for a direct plug-in rechargeable light, as shown and described.

DESCRIPTION

FIG. 1 is a top plan view of a direct plug-in rechargeable light showing my new design;

FIG. 2 is a right side elevational view thereof, the left side being a mirror image;

FIG. 3 is an underneath plan view thereof;

FIG. 4 is a front elevational view thereof;

FIG. 5 is a rear elevational view thereof;

FIG. 6 is a front elevational view thereof, with the head pivoted upwardly and the recharger prongs extended; and

FIG. 7 is a right side elevational view thereof, with the head pivoted upwardly and the recharger prongs extended.

*FIG. 1.**FIG. 2.**FIG. 3.**FIG. 4.**FIG. 5.**FIG. 6.*

FIG. 7.
